(57) **CLAIM**

The ornamental design for a door for bus vehicle, as shown and described.

DESCRIPTION

FIG. 1 is a rear elevational view of a door for bus vehicle; FIG. 2 is a front elevational view of a door for bus vehicle; FIG. 3 is a side elevational view of a door for bus vehicle; FIG. 4 is a side, opposite to the side of FIG. 3, elevational view of a door for bus vehicle;

FIG. 5 is a top elevational view of a door for bus vehicle; FIG. 6 is a bottom elevational view of a door for bus vehicle; and,

FIG. 7 is a perspective view of a door for bus vehicle. The broken lines showing the top and bottom elevation views of a door for bus vehicle are included for the purpose of illustration structure and form no part of the claimed design.

1 Claim, 7 Drawing Sheets
